Application November 26, 1943, Serial No. 511,802

20 Claims. (Cl. 125—11)

The present invention relates to methods and to apparatus for dressing grinding wheels and particularly to a method and apparatus for dressing cup-shaped grinding wheels such as are employed in the grinding of spiral bevel and hypoid gears without generating roll.

In dressing a gear-grinding wheel, it is customary to dress the tip and both sides of the wheel, and the practice is to use separate side and tip-dressing tools for this purpose. The side and tip-dressing tools are ordinarily connected together to perform and complete their respective operations simultaneously. As a result, with the dressing mechanisms employed until quite recently, the tip of a gear-grinding wheel has been dressed to a much finer finish than the sides of the wheel, because the width of the tip of a gear-grinding wheel is always less than the height of the sides of the wheel, and if the side-dressing tools are required to complete their operations in the same period of time as the tip-dressing tool, the tip-dressing tool will naturally move slower and therefore dress a finer finish on the wheel.

This was of no consequence in the automotive field for the bottoms of the tooth spaces of automotive gears and the fillets, which join the tooth space bottoms with the sides of the tooth spaces, are not ground. In the airplane field, however, the tooth space bottoms and the fillets have to be ground, in addition to the sides of the teeth, in order to eliminate all surface cracks. Surface cracks are always points of incipient breakage, particularly under the heavy loads which airplane gears have to carry. It has been discovered that if the tips and rounds of the grinding wheel are dressed too fine, the bottoms and fillets of the tooth spaces of the gears are likely to be burned in the course of grinding. This is dangerous because a burned surface is a surface full of cracks and ripe for breakage under load.

Recently, a dressing mechanism has been devised for dressing rotary annular grinding wheels which will permit of dressing the tips of such wheels simultaneously with the sides of the wheels but with the tip-dresser travelling at a rate faster than the rate of movement of the side-dressers so as to dress the tip of the wheel to a finish approximately the same as the finish dressed on the sides of the wheel and sufficiently coarse so as not to burn the work. Annular wheels are, however, ordinarily used only for grinding spiral bevel and hypoid gears in a generating operation. For grinding spiral bevel and hypoid gears without generating roll, cup-shaped wheels are usual-

ly employed. The problem of dressing the tip of a cup-shaped gear-grinding wheel simultaneously with the sides of such a wheel with a finish no finer than the finish of the sides is a different and much more difficult problem than that of so dressing an annular wheel.

An annular grinding wheel grinds the lengthwise tooth shape on a longitudinally curved tooth gear by simple rotation of the wheel on its axis. The axis of the wheel is perpendicular to the plane of operation. Moreover, the tip of the wheel usually lies in that plane. As a result, the side-dressers employed in dressing an annular grinding wheel can be positioned at one point around the periphery of the wheel and the tip-dresser at another point, and the side and tip-dressers can be operated at different rates of speed without possibility of interference with one another.

20 A cup-shaped gear grinding wheel, however, has to be oscillated about an axis separate from its own axis of rotation in order to grind the lengthwise tooth shape on a longitudinally curved tooth gear. The axis of a cupped wheel has, therefore, to be inclined to its plane of operation, and to avoid excessive and impractical complications in the dressing mechanism and in its adjustment, the side and tip-dressing tools for dressing a cupped wheel have to be arranged to operate at the same point around the periphery of the wheel. In this position, the side and tip-dressing tools can all be operated simultaneously at the same speeds and will clear one another, but they cannot be operated at different speeds

25 without interference. The method, used in the dressing of annular wheels, for obtaining a sufficiently coarse finish on the tips and rounds of the wheel while getting the required fineness of finish on the sides, cannot be applied, therefore to the dressing of cup-shaped wheels.

Beyond this, another problem has arisen in connection with the dressing of cup-shaped gear-grinding wheels. Such wheels ordinarily have side surfaces of straight profile. As the demand for more accurate gears has increased, however, it has become more and more desirable to dress all bevel and hypoid gear-grinding wheels with side surfaces of curved profile to overcome certain tooth bearing conditions encountered on spiral bevel and hypoid gears that have been ground. In the dressing mechanism employed for dressing annular grinding wheels, control of the profile shape can be obtained very readily by adjustment of the position of the axis of swing 30 of the dressing tool up or down to change the

point around the periphery of the wheel at which the dressing tool contacts the wheel. This solution, however, does not resolve the problem for a cupped wheel, for, as already stated, the side-dressing tools and end-dressing tools should dress at the same point around the periphery of the wheel, and this point cannot be changeable without making the whole dressing mechanism excessively complicated.

Aside from the above-mentioned difficulties in 10 the dressing of cup-shaped gear-grinding wheels, there is another feature which has heretofore limited the use of such wheels. In the conventional type of gear-grinding machine employing a cupped wheel, the wheel is journaled in a quill which is oscillated back and forth, as the wheel rotates, to grind the tooth sides of a gear to the desired lengthwise curvature; the dressing mechanism is mounted on the quill housing at one side of and beyond the working path of the wheel; and when it is desired to dress the wheel, the oscillating movement of the quill is stopped and the quill is swung beyond its normal working path to bring the wheel into operative relation with the dressing mechanism. Even though the dressing mechanism has thus been disposed out of the way of the working path of the wheel, on some jobs there is not sufficient clearance between the dressing mechanism and the work support during grinding. This has definitely limited the capacity of spiral bevel and hypoid gear grinders of the non-generating type.

One object of the present invention is to provide a dressing mechanism, particularly for dressing cup-shaped gear grinding wheels, in which the tip of the wheel may be dressed in the same operation as the dressing of the sides of the wheel but with a finish coarse enough to avoid burning of any workpiece ground by the wheel.

Another object of the invention is to provide a dressing mechanism for dressing the sides and tip of a cup-shaped grinding wheel and the rounds, which join the sides with the tip, with which the tip and rounds may be dressed to have approximately the same finish as the sides so that the wheel can be used to grind the sides, bottoms, and fillets of the tooth spaces of a gear to substantially uniform tooth surface finish.

A further object of the invention is to dress the sides and tip of a cup-shaped grinding wheel so that the wheel can grind gears faster without danger of burning than they can be ground by wheels dressed according to conventional practice.

Another object of the invention is to provide a dressing mechanism which may be used to dress the side of a grinding wheel to either a straight or a curved profile shape.

A further object of the invention is to provide a dressing mechanism which may be used to dress a curved profile on a side of a grinding wheel in which the radius of curvature of the profile dressed and its convexity or concavity may be controlled by adjustment of a simple and single control member or cam.

A further object of the invention is to provide a dressing mechanism having side and tip-dressers which is so mounted and operated as to swing out of operative position upon completion of a dressing operation, so as to permit grinding any gear within the capacity of the machine, on which the dressing mechanism is used, without danger of interference of the dressing mechanism with the work or with the work support.

Still another object of the invention is to pro-

vide a dressing mechanism of the character described which is fluid-pressure operated and in which the movements of the side and tip-dressers to and from operative position as well as the operation of these dressers when in operative position can be controlled by a single control valve.

Another object of the invention is to provide a dressing mechanism which can be adjusted readily for dressing wheels of various diameters, heights, pressure angles, and profile shapes.

Other objects of the invention will be apparent hereinafter from this specification and from the recital of the appended claims.

In the drawings:

Fig. 1 is a fragmentary front elevation of a conventional type of spiral bevel and hypoid gear grinding machine, showing the cupped grinding wheel of the machine swung up to dressing position and showing a dressing mechanism constructed according to one embodiment of this invention mounted on the machine and in operative engagement with the grinding wheel;

Fig. 2 is a transverse sectional view through the dressing mechanism and wheel taken in the radial plane of the wheel in which the dressing tools engage the wheel at the mean points of the strokes of the tools;

Fig. 3 is a part elevational and part sectional view, looking at the dressing mechanism from the right hand side of Fig. 2 but with the side-dressing tool and its actuating parts removed;

Fig. 4 is a sectional view taken on the line 4—4 of Fig. 3;

Fig. 5 is a sectional view taken on the line 5—5 of Fig. 3;

Fig. 6 is a sectional view on the line 6—6 of Fig. 1;

Fig. 7 is a section on the line 7—7 of Fig. 1;

Fig. 8 is a detail view showing the eccentric for adjusting the radial position of the tip-dresser;

Fig. 9 is a transverse sectional view of the tip-dresser;

Fig. 10 is a sectional view through one of the side-dressers;

Fig. 11 is a perspective view of one of the adjustable blocks for controlling the profile shapes dressed on the wheel;

Fig. 12 is a diagrammatic view, illustrating the operation of the outside-dresser;

Fig. 13 is a diagrammatic view showing the path of the ball-follower across the control block in the operation of the outside-dresser;

Fig. 14 is a diagrammatic view similar to Fig. 12 illustrating the operation of the inside dresser;

Fig. 15 is a diagrammatic view similar to Fig. 13 showing the path of movement of the ball-follower in the operation of the inside-dresser;

Fig. 16 is a diagrammatic view illustrating the action of the inside, outside, and tip-dressers in the forward movements of these dressers;

Fig. 17 is a similar view showing the action of the side and tip-dressers on their return strokes;

Fig. 18 is a diagrammatic view showing the hydraulic circuit to the various parts of the dressing mechanism; and

Fig. 19 is a section on the line 19—19 of Fig. 18.

In the preferred embodiment of the present invention, the side and end-dressing tools are mounted on three separate, swinging arms that in each dressing operation are swung first forward and then back, and each of which can be moved axially simultaneously with its swing in order to vary the shapes of the surfaces dressed on the wheel. This follows conventional practice.

The tip-dresser is preferably made identical

with the tip-dresser disclosed in the pending application of Ernest Wildhaber, Serial No. 473,067, filed January 21, 1943. It is mounted so that the tip-dressing tool may swing across the tip of the wheel in a generally elliptical path and it is provided with a control cam that can be adjusted to move the dressing tool axially as it swings, whereby to modify the elliptical path and produce a flattened surface on the tip of the wheel with rounds joining the tip with the sides of the wheel.

The side-dressers are in some respects quite similar to prior types of side-dressers, particularly to those employed on generating types of gear grinders for dressing rotary annular wheels. They differ from conventional types of side-dressers, however, in the means employed for controlling the axial movements of the dressing tools. Heretofore, cams have been employed for this purpose, and a different cam has been required whenever a different profile shape is to be dressed. In the side-dressers used in the preferred embodiment of the present invention, control members are used which have plane control surfaces and which are mounted to be adjustable angularly about axes offset from and at right angles to the axes of swing of the two side-dressers. Each side-dresser arm carries a ball follower that rides over the plane surface of its control member as the dresser arm swings back and forth. When the control member is in zero position, its plane surface is at right angles to the axis of swing of the side-dresser arm and no axial movement is imparted to the dresser. Hence a straight profile is dressed on the side of the wheel. When the control member is adjusted angularly, its plane control surface is at an acute or an obtuse angle to the axis of swing of the dresser. In such case, the dresser arm will be moved axially as it swings, and the tool will dress either a convex or a concave surface on the wheel, depending on whether the dresser is the inside or outside dresser and depending on whether the control member is adjusted to an acute or an obtuse angular position. The radius of curvature of the profile dressed depends on the angularity of the position of the control member.

Both side and tip-dressers are fluid-pressure operated. The side-dressers are actuated through movement of a piston which is provided on opposite sides with racks that mesh with spur pinions that are secured to the side-dresser arms. The tip-dresser is actuated through movement of a piston which is provided with a rack that meshes with a spur pinion which is connected to the tip-dresser arm. The side and tip-dresser pistons are connected together, as heretofore, so that they operate at the same speed, and a different ratio of gearing is employed between the side-dresser piston and the side-dresser arms from that employed between the tip-dresser piston and the tip-dresser arm so that the strokes of side and tip-dressing tools can be completed simultaneously.

The side-dressers, their control members, and their operating piston are mounted in a block which is angularly adjustable to permit positioning the dressers in accordance with the pressure angles to be dressed on the inside and outside surfaces of the wheel. This block is mounted on a slide that is adjustable rectilinearly to position the side-dressers radially in accordance with the diameter of the wheel. The tip-dresser, its control cam, and its operating piston are mounted

in a block which is mounted for rectilinear adjustment in two directions at right angles to one another. One adjustment is for positioning the tip-dresser in accordance with the height of the wheel to be dressed. The other adjustment is for positioning the tip-dresser radially of the wheel independently of the radial adjustment of the side-dressers. The block carrying the tip-dresser is pivotally mounted on the same slide that carries the side-dressers. The pivotal support of the tip-dresser block is for moving the tip-dresser into and out of engagement with the tip of the grinding wheel, as will be described further hereinafter. The slide, which supports both the side and end-dressers, is carried by an arm which is pivotally mounted to swing the whole dressing mechanism, including side and end-dressers, into and out of operative position. Both the pivotal movement of the tip-dresser and the pivotal movement of the slide are effected by fluid-pressure operated pistons.

The operation of the several fluid-pressure operated pistons is controlled by a single valve. This valve controls directly the movements of the piston, which moves the dressing mechanism into and out of operative position, and of the pistons, which operate the side and tip-dressers, and it controls through a shuttle valve the piston which moves the tip-dresser into and out of engagement with the wheel. Separate throttle valves govern the rates of movement of the side and tip-dresser pistons in opposite directions.

When it is desired to dress the grinding wheel, the control valve is first moved part-way in one direction to cause the whole dressing mechanism to be swung into operative position. Then the control valve is moved the rest of the way in this same direction causing the two pistons, which actuate the side and tip-dressers, to traverse the side and tip-dressing tools across the sides and tip, respectively, of the wheel. During this operation, the movement of the tip-dresser is throttled by one of the throttle valves so that the tip-dressing tool may swing across the tip of the wheel at a rate sufficiently fast to dress the tip and rounds on the wheel to a finish of desired fineness but still sufficiently coarse as not to burn a gear. Since the side-dresser piston is operatively connected with the tip-dresser piston, its movement is also throttled, but the side-dressers will travel across the sides of the wheel faster than the tip-dressing tool travels across the tip and thus will dress coarser surfaces on the sides of the wheel to provide rough-dressed surfaces. The control valve is then moved back one step, causing the side-dressers to be traversed back across the sides of the wheel at a relatively slow rate under control of the other throttle valve so that they finish-dress the sides of the wheel. Simultaneously, the shuttle valve above referred to is shifted, causing the tip-dressing tool to be disengaged from the wheel so that during its return stroke, it will not dress the wheel at all but will leave the tip and rounds of the wheel with the finish produced on its forward stroke. Usually the two throttle valves are adjusted so that the rates of movement of the side and tip-dressers, respectively, under control of these valves, is substantially the same so that the same finish will be dressed on the sides and tip of the wheel. The dressing operation is now completed. Then the operator moves the control valve back the second step to its original position, causing the bracket, which carries the dressing mechanism, to be swung away from the wheel, to move side

and tip-dressers out of operative position so that they may completely clear the work when the wheel is in use.

Reference will now be had to the drawings for a more detailed description of the invention. 20 denotes the upright or column of the grinding machine, which may be of the general type shown in Bullock et al. Patent No. 2,099,674, granted November 23, 1937. 21 is the oscillatable quill which is journaled in this column, and W is the grinding wheel. The wheel is mounted on a spindle (not shown) that is journaled in the quill 21 with its axis at an angle to the axis of the quill. As already stated, as the grinding wheel rotates on its axis, the quill is oscillated to effect the grinding operation; and when the grinding wheel is to be dressed, the quill is swung beyond its normal working path far enough to bring the wheel into operative relation with the dressing mechanism. This latter position is shown in Fig. 1.

Secured to the column 20, as by means of bolts 28 and 29 (Figs. 3 and 4), are two brackets 15 and 16. Pivotally mounted on these brackets is the support 22 (Figs. 2 and 3). This support is fastened by means of a pin 23 to a shaft 24 which is journaled on anti-friction bearings 25 and 26, respectively, in the brackets 15 and 16 and which serves as the pivot for the support 22.

The support 22 is adapted to be swung about the axis of shaft 24 by fluid-pressure. For this purpose, the shaft 24 is keyed at its lower end to a rotary piston 30 which is mounted to oscillate in a cylinder 31. Also mounted within the cylinder 31 is a partition member 34 which serves to limit the movements of the piston in the cylinder. The cylinder is secured to the bracket 16 by screws 32 and 33 and the partition member 34 is secured to the side wall of the cylinder by screws 35 and the dowel pin 36.

Movement of the support 22 is limited in one direction by a stop 38 which is threaded into the bracket 15 and which is adapted to engage with a hardened stud or pin 39 that is carried by the support 22. Movement of the support 22 in the opposite direction is limited by a stop 40 which engages with a lug 41 that is integral with the support. The stop 38 serves to limit the swing of the dressing mechanism to operative position and the stop 40 serves to limit the swing of the dressing mechanism to inoperative position. A spring-pressed plunger 42, which is housed in the wall of cylinder 31 and which has a beveled head 43, serves to engage behind the lug 41 to resiliently hold the support 22 in inoperative position.

The support 22 is provided with a guide portion 45 and on this there is mounted for rectilinear adjustment a slide 46. This slide is adjusted on the support by means of a screw shaft 47 which is journaled in the support and which threads into a nut 48 (Fig. 5) that is secured to the slide. A scale 76 (Fig. 1), which is secured to support 22 and a pointer 78, that is secured to slide 46, and reads against the scale, and a graduated dial 44, which is secured to the shaft 47, permit of adjusting the slide precisely on the support. The slide may be secured in any adjusted position by bolt 78 (Figs. 1 and 3) which passes through elongated slot 79 formed in slide 46 and which threads into the support 22.

The slide 46 is formed with two forwardly projecting arms in which is journaled on anti-friction bearings 49 and 50 the shaft 51. Secured to this shaft is a block 52 (Figs. 3 and 5) which is adapted to be rocked about the axis of the shaft 51. For this purpose, the block 52 is bored to

provide a cylinder 53 (Figs. 3 and 6) in which is mounted a reciprocable piston 54. This piston is formed with a portion 56 which projects through one end wall 61 of the cylinder 53 and which engages a hardened stop button 57 that is mounted in the slide 46. The piston is formed at its other end with a portion 58 which engages a hardened stop button 59 that is mounted in the other end wall 60 of the cylinder 53.

The movements of the piston 54 are controlled by a shuttle valve 62 which is mounted to reciprocate in a sleeve 64. This sleeve is secured in a hole bored in block 52 parallel to cylinder bore 53. The valve 62 is constantly urged in one direction by a coil spring 65 that is mounted in a recess in the valve and that seats at one end against the end-plate 61. The sleeve 64 is provided with three series of radial ports that are denoted at 66, 67, and 68, respectively. The pressure fluid is admitted to the valve 62 through a pressure line 70 and is exhausted from the valve through an exhaust line 71. The valve is shiftable against the resistance of the spring 65 by admission of the pressure fluid to the head of the valve through the line 73. The ports 67 of the valve sleeve are connected with one side of the piston 54 through a duct 75. In the position shown in Figs. 6 and 18, the duct 75 is on supply from the line 70 through ports 66 and 67. When the valve 62 is shifted, the duct 75 is put on exhaust through ports 67 and 68 and line 71.

The block 52 is constantly urged in one direction about the axis of shaft 51 by a coil spring 80 (Fig. 7) which seats at one end in a recess formed in the slide 46 and at its opposite end in a nut 81 that threads into the block 52. When the duct 75 is on supply, however, the block 52 is rocked about the axis of shaft 51 against the resistance of the spring 80. A stop button 82 (Fig. 7), which is carried by the block 52 and which engages with a stop button 83 that is carried by the slide 46, serves to limit the rocking movement of block 52 under fluid-pressure.

Mounted on the block 52 for rectilinear adjustment thereon is a right angle shaped bracket 85 (Figs. 3 and 5). The bracket 85 is secured to the block 52 by T-bolts 86 and 87 whose heads engage in a T-slot 88 formed in the face of the block 52. The T-bolt 87 is mounted in an eccentric sleeve 89 which is rotatable in an elongated slot 91 (Fig. 8) formed in the bracket 85. Rotation of the eccentric 89 permits fine adjustment of the bracket 85 on the block 52. This serves for positioning the radial position of the end-dresser independently of the radial adjustment of the side-dressers, as will be described later. This is an important feature of the mechanism since it enables the tip-dressing tool to be adjusted so that the rounds dressed thereby may blend with the sides of the wheel without any shoulders being formed.

Mounted on the bracket 85 for rectilinear adjustment thereon in a direction at right angles to the direction of adjustment of the bracket itself is the housing 90 which supports the tip-dresser and its operating parts. This housing may be adjusted on the bracket 85 by rotation of the screw shaft 107 (Fig. 5) which is journaled in the bracket 85 and which threads into a nut (not shown) that is secured in the housing. This adjustment can be made precisely through use of the graduated dial 108 which is secured to shaft 107 and through use of a pointer 118 (Fig. 3) which is secured to bracket 85 and which reads against a scale 119 that is fastened

to housing 90. The housing is secured in any adjusted position by bolts 109 which pass through elongated slots in bracket 85 and which thread into housing 90.

As already stated, the tip-dresser shown is of the construction disclosed in the pending application of Ernest Wildhaber, Serial No. 473,067, filed January 21, 1943. The tip-dressing tool 92 is clamped in an arm 93 (Fig. 9) that is mounted on a sleeve 94 to be angularly adjustable thereon but to be clamped thereto after adjustment. The sleeve 94 is mounted on a shaft 96 and is keyed thereto. It is formed with clutch teeth on its inner end to engage with clutch teeth formed on the opposing end face of a sleeve 95. The sleeve 95 is also mounted on shaft 96. The tip-dresser housing 90 is so mounted on the bracket 85 that the axis of shaft 96 is inclined at other than right angles to the tip-plane of the grinding wheel, so that the dressing tool may dress an elliptical shape as the tool swings across the tip of the wheel.

The sleeve 95 is adapted to be rotated, to swing the tool 92 from side to side across the tip of the wheel, by movement of a piston 97 which has rack teeth formed on one side to mesh with the teeth 98 of a spur pinion that is integral with the sleeve 95. The shaft 96 is formed with an arm 99 on its rear end which carries a follower 100. The follower engages the active surface of a cam member 101 which is rectilinearly adjustable in the housing 90 in a direction at right angles to the axis of the shaft 96. This adjustment is effected by rotation of the screw shaft 102 which threads into a nut 103 that is carried by the cam member 101. This adjustment can be made precisely by means of a graduated dial 104 which is secured to shaft 102 and by means of the index pointer 105 (Fig. 1) which is secured to the cam member 101 and which reads against the graduated scale 106 that is secured to the housing 90.

The cam member 101 may have an active surface which is in part plane and in part of toric shape, as described in the Wildhaber application above mentioned. As the shaft 96 is revolved, therefore, to swing the dressing tool 92 from one side of the wheel to the other across the tip of the wheel, the shaft 96 will be moved axially to modify the elliptical shape which it would otherwise produce, and form a flattened surface on the tip of the wheel with rounds where the tip surface joins the sides of the wheel. The coil spring 105, which surrounds the shaft 96 and which is interposed between the housing and the arm 99, serves to hold the follower 100 in engagement with the cam 101.

The side-dressers and their actuating parts are mounted in the block 110 (Figs. 1 and 2) which is mounted on the slide 46 for angular adjustment thereon. This adjustment is effected by rotation of a worm shaft 111 which is journaled in the block 112. This block is secured to the slide 46 by means of bolts 113. The worm shaft 111 carries a worm 114 that meshes with a worm wheel segment 115 which is secured to or integral with the block 110. The block 110 is secured in adjusted position by means of bolts 116 which pass through arcuate slots 117 formed in the block 110 and which thread into the slide 46.

Mounted in the block 110 for axial and oscillatory movement therein, are the two shafts 120 and 121 which carry the outside and inside-dressing tools 122 and 123, respectively. The

tool 122 is mounted in an arm 124 that is secured in any suitable manner to the shaft 120 and the tool 123 is mounted in an arm 125 that is secured in any suitable manner, as by means of the screw 126, to the shaft 121.

The shafts 120 and 121 are perpendicular to the outside and inside surfaces, respectively, of the wheel. They are oscillated by reciprocation of the piston 127 (Figs. 2 and 18) which is provided on opposite sides with rack teeth that mesh with spur gear segments 129 and 130, respectively, which are secured to shafts 120 and 121, respectively.

During their oscillation, the shafts 120 and 121 may also be moved axially. The axial movements of the shafts are effected through operation of angularly adjustable control members 134 and 135 (Figs. 10, 11, 12 and 14) which are identical with one another. Each of the control members is formed with spaced trunnions 137 which are mounted in suitable bearings provided in the side walls of the housing 110. Between the trunnions 137, each control member is slabbed off to provide a plane control surface 138. Each of the shafts 120 and 121 is provided with an arm 139, and in each of these arms is mounted the ball-shaped follower 140 that engages the plane surface 138 of a control member. The axis of adjustment of the control member passes through the center of the spherical surface of the ball-shaped follower in the middle position of swing of the ball. Each follower 140 is held in engagement with the surface 138 of the corresponding control member by a coil spring 142 which is housed in a recess in the shaft 120 or 121, as the case may be, and which is interposed between the bottom of this recess and the head of a plunger 143 which is secured in the shaft 120 or 121.

Figs. 12 to 15 inclusive illustrate diagrammatically how the control members function in the dressing of the outside and the inside surfaces of the grinding wheel. In Fig. 12, the control member 134 is shown tilted rearwardly. As the follower 140 travels across the plane face 138 of the control member in the swing of the shaft 120, the point of contact of the follower with the control member will trace an arcuate path 145 and the shaft 120 will first be moved rearwardly and then will be moved forwardly again. Thus a convex surface 146 will be formed on the wheel by the outside dressing tool 122.

In Fig. 14, the control member 135 is also shown tilted rearwardly and set at the same angle as the control member 134. As the shaft 121 is oscillated, the follower 140 will trace the arcuate line of contact 148 on the plane surface 138 of the control member and again the dressing tool will first be moved rearwardly and then forwardly again. Since the dressing tool 123 is operating on the inside surface of the wheel, it will thus dress a concave profile shape 147 on the wheel.

In Figs. 12 and 14, the wheel W' is shown in section in the plane of the drawings. This is for the purpose of illustration as the wheel, of course, would be perpendicular to the plane of the drawings when the axes 120 and 121 are in the plane of the drawings.

By setting the control members 134 and 135 to different angles, inside and outside surfaces can be dressed on the wheel having different radii of curvature. When either control member is set to the zero position of its adjustment, there will be no axial movement of the dressing tool

as it swings across the surface being dressed, and the surface dressed will be of approximately straight profile shape.

For adjusting the angular position of each control member, a graduated plate 150 (Fig. 1) is provided. This plate is mounted on the projecting hub portion 151 (Fig. 11) of the control member and is secured thereto by a nut 152. The plate 150 is beveled off at its lower end and provided with graduations to read against an index marked on the side of the housing 110. The plate is secured in any adjusted position by means of a bolt 153 which passes through an arcuate slot 154 in the plate and which threads into the housing 110.

One way in which the various fluid-pressure operated parts may be connected is shown in Fig. 18. The operation of these parts is controlled by a manually rotatable valve 160 which is journaled in a sleeve 161 that is mounted in a housing 162. This valve is adapted to be manipulated by a handle 164 which is secured to its projecting stem portion 165. The housing 162 may be fastened at any convenient point on the grinding machine.

The pressure fluid is supplied to the valve 160 from the line 170 through the duct 171. The line 170 also connects with the line 70 that leads to the shuttle valve 62. The motive fluid is exhausted from the valve casing 162 through ducts 172 and 173 which connect with the duct 174 that leads back to the sump of the machine. The valve is connected to opposite sides of the rotary piston 30 (Figs. 3, 4, and 18), which serves to move the dressing mechanism into and out of operative position, by the ducts 182 and 183. The valve is connected to one side of the piston 127 (Figs. 2 and 18), which actuates the side-dressers, by the duct 185. The valve is connected to one side of the piston 97 (Figs. 9 and 18), which actuates the tip dresser, by the duct 186. The other sides of the pistons 127 and 97 are connected by a duct 191. The duct 186 communicates with the duct 73 that leads to one side of the shuttle valve 62 (Figs. 6 and 18).

The valve 160 shown is of the same construction as the control valve disclosed in the pending application of Paul Barker et al., Serial No. 496,452, filed July 28, 1943. It is provided with two diametrically opposite elongated grooves 175 and with two pairs of diametrically opposed shorter grooves 176 and 177. The elongated grooves 175 are connected moreover by a groove 178 which extends around the whole periphery of the valve.

In the starting position of the valve, the lines 183 and 186 are on supply and the lines 182 and 185 on exhaust. As the valve is rotated, the duct 182 is first put on supply from the line 171 and the duct 183 is put on exhaust. The duct 186 remains, however, on supply and the duct 185 on exhaust. When the duct 182 is put on supply, the rotary piston 30 is moved to the full line position shown in Fig. 18 to swing the whole dressing mechanism into operative position.

When the dressing mechanism is in operative position, the valve 160 is rotated a step further to put the duct 185 on supply and the duct 186 on exhaust while maintaining the duct 182 on supply and the duct 183 on exhaust. The line 185 leads to the upper end of the cylinder 190 which is formed in the block 110. The pressure fluid flowing from the duct 185 into the cylinder 190 forces the piston 127 downwardly to swing the outside dresser 122 across the outside surface

of the grinding wheel from the base to the tip of the wheel and to swing the inside-dresser 123 across the inside surface of the wheel from the tip to the base of the wheel. As the piston 127 moves downwardly, also, the motive fluid in the lower end of the cylinder 190 is forced out through the duct 191 into the cylinder 192 in which the piston 97, that actuates the tip-dresser, reciprocates. This causes the piston 97 to be moved to the left (Fig. 18) in this cylinder, forcing the motive fluid out of the left-hand end of this cylinder. There are two ducts 194 and 196 which lead from the left-hand end of this cylinder and which connect with duct 186. The motive fluid flowing from the left-hand end of cylinder 192 cannot flow through the duct 194 because this duct is closed by a ball check valve 195; it must flow through the duct 196. The connection of duct 196 with the duct 197 is controlled, however, by an adjustable needle valve 198. Hence, the movement of piston 97 and of the tip-dresser 92, which it operates, is throttled. The setting of needle valve 198 determines the rate of movement of the tip-dresser across the tip and rounds of the wheel and the finish which is dressed on the tip and rounds of the wheel.

At this time, also, the shuttle valve 62 is held in the position shown in Figs. 6 and 18 by the coil spring 65, for the line 73 which connects with line 186 is like line 186 on exhaust. This allows the pressure fluid to flow from the duct 70 through the ports 66 and 67 (Figs. 6 and 18) of sleeve 64 into the duct 75 that leads to one end of the piston 54. This causes the block 52 (Figs. 5 and 6) to be swung about the axis of the shaft 51 to cause the tip-dresser to be moved into and to be held in operative relation with the grinding wheel. Thus as the tip-dresser 92 moves in one direction during the movement of piston 97 from right to left (Fig. 18), the tip-dresser is held in engagement with the wheel by pressure of the motive fluid on piston 54, and the tip and rounds of the wheel are dressed at a rate determined by the setting of needle valve 198.

45 The operator now reverses the direction of movement of the control valve 160, moving it back one step. This now puts the line 186 on supply and the line 185 on exhaust while maintaining the duct 182 on supply and the duct 183 on exhaust. The pressure fluid flowing from the line 186 through the duct 73 forces the shuttle valve 62 to the right from the position shown in Fig. 18 against the resistance of the spring 65. This shuts off the connection of the duct 70 with duct 75 and connects the duct 75 with the exhaust duct 71. This allows the spring 80 (Fig. 7) to rock the tip-dresser about the axis of the shaft 51, to move the tip-dresser away from engagement with the grinding wheel.

60 At the same time, the pressure fluid flowing through the duct 186 enters the left-hand end of the cylinder 192 through the duct 196 and also through the duct 194, the check valve 195 being forced open by the pressure of the motive fluid. This causes the piston 97 to be moved back to the right in cylinder 192 and it causes the tip-dresser 92 to be swung back to its starting position. Now as the piston 97 moves back to the right, the motive fluid is forced out of the right hand of the cylinder 192 through the line 191 into the lower end of the cylinder 190. This forces the piston 127 upwardly, rocking the side-dressers back across the outside and inside surfaces of the grinding wheel to their starting positions. Now in the upward movement of piston

127, the motive fluid is forced out of the upper end of the cylinder 190 through the line 185.

The duct 185 has two connections with the valve 160. One is through the duct 205 which is only open when the duct 185 is on pressure and which at this stage is closed by the ball check valve 204 through operation of spring 202 and the pressure of the motive fluid on the ball. The other is through the duct 203, needle valve 200 and duct 204. The latter connection is operative at this time and the rate of the return movement of the side-dressers is therefore controlled by the setting of the needle valve 200. Thus the return strokes of the side-dressers may be controlled to effect finish-dressing of the sides of the wheel. By suitable adjustment of the needle valves 198 and 200 the forward stroke of the tip-dresser and the return strokes of the side-dressers can be at the same rate, and then the wheel will be dressed to have the same finish on its sides, tip, and rounds.

When the side and tip-dressers have finished their return strokes the dressing operation will have been completed. The operator now moves the valve 160 back to its original position, putting the line 183 on pressure and the line 182 on exhaust, while maintaining the duct 186 on supply and the duct 185 on exhaust. The pressure fluid flowing through the duct 183 swings the piston 30 from the full line position shown in Fig. 18 to the dotted line position shown in that figure and thus, the whole dressing mechanism is swung away from operative to inoperative position. The dressing cycle has been completed.

In dressing any grinding wheel, the dressing tool turns a helical groove in the surface being dressed as the tool travels across the surface of the rotating wheel, and the rate of travel of the dressing tool across the surface being dressed determines the lead of this groove and, consequently, the finish which is dressed on the surface.

The principle of operation of the dressing mechanism of the present invention is illustrated diagrammatically in Figs. 16 and 17 in connection with the dressing of a grinding wheel W^2 whose side surfaces are of straight profile shape. In the first stage of the dressing operation, as already described, the outside-dressing tool 122 moves from the base to the tip of the wheel while the inside-dressing tool 123 is moving from the tip to the base of the wheel and while the tip-dressing tool is moving over the tip of the wheel from outside to inside. In other words, outside-dressing tool 122 swings from a position such as is denoted in dotted lines at 122a in Fig. 16 to a position such as is shown in full lines at 122b, while the inside-dressing tool 123 is swinging from a position such as shown in dotted lines at 123a to a position such as is shown in full lines at 123b, and while the tip-dressing tool 92 is swinging from dotted line position 92a to full line position 92b. In these movements, the tip of the outside-dressing tool travels in the plane 157, the tip of the inside-dressing tool travels in the plane 158 and the tip of tip-dressing tool is travelling in an arc parallel to arc 159 and containing the tip of the wheel. The rate of the described movement of the tip-dressing tool is controlled by the setting of the needle valve 198, and this is adjusted so that a helical surface will be dressed on the tip of the wheel whose lead P' is sufficiently fine to obtain the desired smoothness of finish in the bottoms and fillets of the tooth spaces of a gear without burning. The throttle valve 198 also controls indirectly the described movements 75

of the side-dressers for the circuit 185-191-186 (Fig. 18) is a substantially closed circuit. The side-dressers 122 and 123 have to travel, however, a greater distance in completing a stroke than the tip-dresser travels, for the height of the sides of the wheel is greater than the width of the tip of the wheel. The side-dressers have to travel faster than the tip-dresser, therefore, in order that all the dressers may complete their strokes in the time allowed by the needle-valve 198 for the completion of the stroke of the tip-dresser. The faster rate of travel of the side-dressers is obtained by proper selection of the gearing between the piston 127 and the shafts 120 and 121 (Fig. 2) as compared with the gearing between piston 97 and sleeve 95 (Fig. 9). The faster travel of the side-dressers, however, causes the side-dressing tools to turn helical grooves in the outside 155 and inside 156 of the wheel whose lead P is coarser than the lead P' of the surface dressed on the tip and rounds of the wheel. Thus, the outside and inside surfaces of the wheel are rough-dressed, while the tip and rounds of the wheel are being finish-dressed.

When the directions of movements of the several dressing tools are reversed, the outside-dressing tool swings back through the plane 157 to its original position 122a shown in full lines Fig. 17, the inside-dressing tool 123 swings back through the plane 158 to the full line position 123a shown in Fig. 17, and the tip-dressing tool swings back to the position 92a. In its return movement, the tip-dressing tool does not contact the grinding wheel for it is swung away by action of piston 54 (Figs. 6 and 18) on the pivotal block 52 which supports the tip-dresser. The rates of the return movements of the outside and inside-dressers is controlled by the setting of needle valve 200 (Fig. 19). This valve is adjusted so that the side-dressers may dress surfaces of sufficiently fine finish on the outside and inside of the wheel to grind the desired finish on the side tooth surfaces of a gear to be ground. Preferably, the valve 200 is adjusted so that the rates of movement of the inside and outside-dressers on their return strokes will equal the rate of movement of the tip-dresser on its forward stroke and the lead P' of the finished dressed side surfaces of the wheel may equal the lead P' of the surface previously dressed on the tip of the wheel. Thus, the wheel can grind a substantially uniform finish on the sides, bottoms and fillets of the tooth spaces of a gear.

The operation of the dressing mechanism of this invention will be understood from the preceding description but may be briefly summed up here.

First, of course, the operator makes the various adjustments required. Thus, the control members 134 and 135 (Figs. 10, 11, and 12 to 15) are adjusted in accordance with the profile shapes desired on the outside and inside surfaces of the wheel; the cam 101 (Fig. 9) is adjusted in accordance with the shape desired on the tip of the wheel; the block 110 (Fig. 2) is adjusted to position the side-dressing tools so that they will dress the required pressure angles on the sides of the wheel; the slide 46 (Fig. 2) is positioned so that the side-dressers will have the correct radial positions when in operative positions; the tip-dresser housing 90 is adjusted on the bracket 85 (Figs. 3 and 5) so that the tip-dressing tool 92 will be in correct position, in accordance with the height of the wheel, to engage the tip of the wheel; the bracket 85 is adjusted on the block

52 by adjustment of disc 88 (Figs. 5 and 8) to position the tip-dressing tool radially independently of the radial adjustment of slide 46, above mentioned, so that the surface dressed by the tip-dressing tool may blend with the surfaces dressed by the side-dressing tool; and the throttle valves 198 and 200 (Fig. 18) are adjusted to insure that surfaces of the proper finish will be dressed on the sides, tip and rounds of the wheel. The dressing mechanism is then ready for use.

The grinding wheel is swung to dressing position by movement of the quill 21 (Fig. 1). To dress the wheel, the operator moves the dressing mechanism into operative position by moving the control valve 160 one step. This puts duct 182 (Fig. 18) on supply and duct 183 on exhaust to cause rotary piston 30 to swing support 22 (Fig. 3) about the axis of shaft 24 and move the whole dressing mechanism into operative relation with the grinding wheel. When this has been done, the operator moves control valve 160 a second step. This puts duct 185 on supply and duct 186 on exhaust. The tip-dresser is moved into operative relation with the tip of the wheel through application of fluid pressure to piston 54 (Figs. 6 and 18) to swing the block 52 about the axis of shaft 51 (Figs. 3 and 5) against the resistance of spring 80 (Fig. 7), and the side and tip-dressers are moved across the wheel surfaces through action of the pistons 127 and 97 (Fig. 18). In these movements, the needle valve 198 is operative to determine the rate of movement of the tip-dresser and the finish dressed on the tip of the wheel. Then, the operator reverses control valve 160 one step to put duct 186 on supply and duct 185 on exhaust. This produces the return strokes of the side and tip-dressing tools. During their return strokes, the side-dressing tools dress the sides of the wheel to a finish determined by the setting of the needle valve 200, but the tip-dressing tool is out of engagement with the wheel because the duct 73 (Fig. 18) is on supply and duct 75 is on exhaust and the spring 80 (Fig. 7) therefore swings block 52 and the tip-dresser away from the wheel. The dressing operation having been completed, the operator now moves control valve 160 back to original position to put duct 183 on supply and duct 182 on exhaust to cause rotary piston 30 to swing the whole dressing mechanism about the axis of shaft 24 (Fig. 3) to inoperative position.

While the invention has been described in connection with the dressing of a cup-shaped wheel, it may be employed in dressing other types of wheels, also, for instance, disc wheels and annular wheels. Further, it will be understood that while the invention has been described in connection with a particular embodiment thereof, it is capable of various modifications, and this application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the limits of the invention or the scope of the appended claims.

Having thus described our invention, what we claim is:

1. The method of dressing a grinding wheel which comprises moving a side and a tip-dressing tool across a side and the tip of the wheel, respectively, in one direction, and then reversing

the direction of movement of the tools and maintaining the side-dressing tool in engagement with the wheel during its return stroke but withholding the tip-dressing tool from engagement with the wheel on its return stroke.

2. The method of dressing a grinding wheel which comprises moving a side and a tip-dressing tool across a side and the tip of the wheel, respectively, in one direction, and then reversing the direction of movement of the tools and maintaining the side-dressing tool in engagement with the wheel during its return stroke but withholding the tip-dressing tool from engagement with the wheel on its return stroke, the rate of the return movement of the side-dressing tool being different from the rate of forward movement of said tool.

3. The method of dressing a grinding wheel which comprises moving a side and a tip-dressing tool across a side and the tip of the wheel, respectively, in one direction, and then reversing the direction of movement of the tools, and maintaining the side-dressing tools in engagement with the wheel during its return stroke but withholding the tip-dressing tool from engagement with the wheel on its return stroke, the rate of return movement of the side-dressing tool being different from the rate of forward movement of said tool and being approximately the same as the rate of forward movement of the tip-dressing tool.

4. The method of dressing a grinding wheel which comprises dressing a side of the wheel at one rate of speed and the tip of the wheel at a faster rate, and redressing the side of the wheel at a faster rate of speed than said first named rate of speed.

5. The method of dressing a grinding wheel which comprises passing a dressing mechanism in one direction around a side and the tip of the wheel, and then reversing the direction of movement of the dressing mechanism but withholding the dressing mechanism from engagement with the tip of the wheel during its return stroke, the rate of return movement of the dressing mechanism being faster than the rate of its forward movement.

6. The method of dressing a cup-shaped grinding wheel which comprises moving a side-dressing tool across the outside of the wheel from the base to the tip of the wheel while moving a second side-dressing tool across the inside of the wheel from the tip to the base of the wheel and a tip-dressing tool across the tip of the wheel from outside to inside thereof, and then reversing the directions of movements of all three dressing tools to redress the sides of the wheel during the return strokes of the outside and inside-dressing tools, but withholding the tip-dressing tool from engagement with the wheel during its return stroke, the rates of the return movements of the outside and inside tools being faster than the rates of their forward movements, and the three tools being so positioned that at substantially mean points in their strokes they lie in the same radial plane of the wheel.

7. The method of dressing a cup-shaped grinding wheel which comprises moving a side-dressing tool across the outside of the wheel from the base to the tip of the wheel while moving a second side-dressing tool across the inside of the wheel from the tip to the base of the wheel, and the tip-dressing tool across the tip of the wheel from the outside to the inside thereof, and then reversing

the directions of movements of all three dressing tools to redress the sides of the wheel during the return strokes of the outside and inside-dressing tools, but withholding the tip-dressing tool from engagement with the wheel during its return stroke, the rates of the return movements of the outside and inside tools being faster than the rates of their forward movements and approximately the same as the rate of the forward movement of the tip-dressing tool, and the three tools being so positioned that at approximately mean points in their strokes they all lie in the same radial plane of the wheel.

8. Mechanism for dressing the side and tip surfaces of a rotary grinding wheel comprising a support, a dressing tool reciprocably mounted on the support for dressing one side of the wheel, a second dressing tool reciprocably mounted on the support for dressing the tip of the wheel, means for reciprocating the tools, means for withdrawing the tip-dressing tool from engagement with the wheel on its return strokes, and means for adjusting the rates of movement in opposite directions of the two tools.

9. Mechanism for dressing the side and tip surfaces of a rotary grinding wheel comprising a support, a pair of dressing tools mounted on said support and adapted to dress a side and the tip of the wheel, respectively, fluid pressure operated means comprising a cylinder and a piston reciprocable therein for reciprocating each of said dressing tools, said pistons being so connected together that movement of one causes movement of the other, independently adjustable throttle valves for controlling the rates of movement of the two pistons in opposite directions, respectively, and means controlling the positions of the two dressing tools so that the side-dressing tool is in operative engagement with the wheel during its strokes in both directions, and the tip-dressing tool is in operative engagement with the wheel during its strokes in one direction only and is out of operative position during its strokes in the other direction.

10. A dressing mechanism for grinding wheels comprising a support, a block pivotally mounted on said support, a dressing tool mounted on the block, means for reciprocating the dressing tool, and means for rocking the block about its pivot to cause the tool to engage the wheel to be dressed on movement of the tool in one direction and to be disengaged from the wheel during movement of the tool in the opposite direction.

11. A dressing mechanism for grinding wheels comprising a support, a block pivotally mounted on said support, a dressing tool mounted on the block, fluid-pressure operated means for reciprocating the tool, fluid-pressure operated means for rocking the block about its pivot to cause the tool to engage the wheel to be dressed on movement of the tool in one direction, means for rocking the block about its pivot to cause the tool to be disengaged from the wheel during movement of the tool in the opposite direction, and valve means for controlling the timed operation of the two fluid-pressure operated means.

12. A dressing mechanism for grinding wheels comprising a support, a slide mounted on the support for adjustment radially of the wheel axis, a pair of side-dressing tools movably mounted on the slide for dressing opposite sides of the wheel, respectively, a tip-dressing tool movably mounted on the slide for dressing the tip of the wheel, means for actuating the side-dressing tools to dress opposite sides of the wheel, and means for

75 swinging the tip-dressing tool back and forth from one side of the wheel to the other to dress the tip of the wheel, said tip-dressing tool being mounted on said slide for adjustment radially of the wheel independently of the radial adjustment of said slide.

13. A dressing mechanism for grinding wheels comprising a support, a side-dressing tool reciprocably mounted on said support, a carrier reciprocably mounted on the support, a tip-dressing tool reciprocably mounted on the carrier, a cylinder and a piston reciprocable therein for actuating the side-dressing tool, a cylinder and piston reciprocable therein for actuating the tip-dressing tool, said cylinders being connected by a hydraulic circuit which is substantially closed and so constructed that movement of one piston in its cylinder causes movement of the other piston in its cylinder, a cylinder and a piston reciprocable therein for actuating said carrier to move the tip-dressing tool to and from engagement with the wheel, a reversible shuttle valve controlling the direction of movement of the last named piston, and a single reverse valve controlling the 20 directions of movement of the first two named pistons and of said shuttle valve.

14. A dressing mechanism for grinding wheels comprising a support, a side-dressing tool reciprocably mounted on the support, a carrier reciprocably mounted on the support, and a tip-dressing tool reciprocably mounted on the carrier, a cylinder and a piston reciprocable therein for actuating the side-dressing tools, a cylinder and a piston reciprocable therein for actuating the tip-dressing tool, said cylinders being connected by a hydraulic circuit which is substantially closed and so constructed that movement of one piston in its cylinder causes movement of the other piston in its cylinder, a cylinder and a piston reciprocable therein for actuating said carrier to move the tip-dressing tool to and from engagement with the wheel, a reversible shuttle valve controlling the direction of movement of the last named piston, a single reverse valve controlling 35 the directions of movement of the first two named pistons and of said shuttle valve, and separately adjustable throttle valves for controlling the rates of movement in opposite directions of the first two named pistons.

15. In a grinding machine, a support, a grinding wheel rotatably mounted on the support, a dresser carrier movably mounted on the support, a side-dressing tool and a tip-dressing tool movably mounted on said carrier, fluid-pressure operated means for moving the carrier in opposite directions to move the dressing tools into and out of operative relation with the wheel, fluid-pressure operated means for actuating each of the dressing tools, when in operative position, and a 55 single control valve for controlling the operations of all fluid-pressure operated means.

16. In a grinding machine, a support, a grinding wheel rotatably mounted on the support, a dresser carrier movably mounted on the support, a block movably mounted on the carrier, a side-dressing tool movably mounted on the carrier, a tip-dressing tool movably mounted on said block, means for moving the carrier in opposite directions to move the dressing tools into and out of operative relation with the wheel, means for reciprocating the tools, when in operative position, to effect dressing of the wheel, and means for moving the block on the carrier to move the tip-dressing tool into and out of engagement with 70 75

the wheel independently of the movement of the carrier.

17. In a grinding machine, a support, a grinding wheel rotatably mounted on the support, a dresser carrier movably mounted on the support, a block movably mounted on the carrier, a side-dressing tool movably mounted on the carrier, a tip-dressing tool movably mounted on the block, fluid-pressure operated means for moving the carrier in opposite directions on the support to move the dressing tools into and out of operative relation with the wheel, fluid-pressure operated means for reciprocating the tools, when in operative position, to effect dressing of the wheel, fluid-pressure operated means for moving the block on the carrier to move the tip-dressing tool into and out of engagement with the wheel, and a single control valve controlling all said fluid-pressure operated means.

18. In a grinding machine, a support, a grinding wheel rotatably mounted on the support, a dresser carrier rotatably mounted on the support, a block movably mounted on the carrier, a side-dressing tool movably mounted on the carrier, a tip-dressing tool movably mounted on the block, a cylinder and a piston reciprocable therein for moving the carrier in opposite directions to move the dressing tools into and out of operative relation with the wheel, a pair of cylinders and a pair of pistons reciprocable therein for reciprocating the tools, when in operative position to effect dressing of the wheel, a cylinder and a piston reciprocable therein for moving the block on the carrier to move the tip-dressing tool into and out of engagement with the wheel independently of the movement of the carrier, and a single control valve controlling all of said fluid-pressure operated means and operable first to move the carrier into operative position, then to move the dressing tools in one direction across the wheel, then to move the dressing tools in the opposite direction while the tip-dressing tool is disengaged

from the wheel but the side-dressing tool is in engagement with the wheel, and then to move the carrier to move both tools out of operative position, and separate, independently adjustable throttle valves for controlling the rates of movement in opposite directions, respectively, of the two pistons which actuate the dressing tools.

19. A dressing mechanism for grinding wheels comprising a support, a shaft mounted in said support for rotary and axial movement about an axis perpendicular to a side of the wheel, an arm secured to said shaft at one end thereof, a dressing tool carried by the arm and adapted to dress a side of the grinding wheel, a second arm secured to the opposite end of said shaft, a control member having a plane control surface mounted on said support for angular adjustment about an axis perpendicular to the axis of the shaft to vary the inclination of its control surface to the axis of the shaft, a follower carried by said second arm and adapted to engage said control member, and means for oscillating the shaft.

20. A dressing mechanism comprising a support, a shaft mounted on said support for rotary and axial movement about an axis perpendicular to a side of the wheel, an arm secured to said shaft at one end thereof, a dressing tool carried by said arm and adapted to dress a side of the grinding wheel, a second arm secured to the opposite end of the shaft, a control member having a plane control surface mounted on said support for angular adjustment about an axis perpendicular to the axis of said shaft to vary the inclination of said control surface to the axis of the shaft, a ball follower carried by said second arm and adapted to engage said control member, the center of said ball lying on the axis of adjustment of the control member, and means for oscillating the shaft.
